UNITED STATES PATENT OFFICE.

GEORGE F. PAWLING, OF PHILADELPHIA, PENNSYLVANIA.

SKELETONIZED JOIST.

Application filed July 8, 1925, Serial No. 42,118. Renewed January 6, 1928.

The present invention stated in its broadest terms relates to building construction, particularly floor and ceiling structures, and has more especial relation to skeletonized joist therefor.

The leading object of the present invention is to provide skeletonized joist which while cheaper and lighter than conventional bar joist is possessed of great structural strength,

A further object is to provide skeletonized joist which may be manufactured at a central plant in various sizes scientifically planned to meet varied building requirements so that said different, predetermined sizes of joist may be shipped to the contractor ready for erection without waste of joist material as is now quite common practice in this art.

Another object is to provide skeletonized joist provided at the place of manufacture with pins or studs for the more expeditious and uniform attachment of metal lath.

Other and further objects of the present invention reside in the provision of general details of construction and arrangement and combination of parts for attaining the results sought by the foregoing objects.

The invention consists of the novel constructions hereinafter described and finally claimed.

The nature, characteristic features and scope of the invention will be more fully understood from the following description taken in connection with the accompanying drawings forming part hereof, and in which:

Fig. 1, is a view in a side elevation of skeletonized joist embodying the invention

Fig. 2, is a top or plan view thereof.

Fig. 3, is a view in cross-section taken upon the line 3-3 of Fig. 1; and

Fig. 4, is a detail view of one of the vertical struts.

For the purpose of illustrating my invention I have shown in the accompanying drawings one form thereof which is at present preferred by me, since the same has been found in practice to give satisfactory and reliable results, although it is to be understood that the various instrumentalities of

which my invention consists can be variously arranged and organized and that my invention is not to be limited to the precise arrangement and organization of the instrumentalities as herein shown and described.

In the drawings the upper chord of my

skeletonized joist as clearly shown in Fig. 3 is of T-shaped cross-section having a vertical web 1 and a broad flat top 2. In practice this top chord is planned to meet predetermined requirements. For example, when the contractor is erecting a building he has merely to designate to the manufacturer of the joist at a central plant the dimensions between supporting girders and the approximate weight to be sustained and properly proportioned skeletonized joist will be shipped to the contractor so that waste by overlapping joist ends (as is now common practice) is eliminated. The lower chord of the joist comprises a pair of spaced bars 3-4 of circular cross-section. The major portion of these bars 3-4 parallel the top chord and the respective ends of each bar are inclined as at 5 and are secured to the web of the top chord to support said inclined ends. The remaining portion of the lower chords are supported by means of vertical struts or compression members 6. These struts are formed preferably as flat, web-like pieces the width of which is substantially equal to the width of the top 2 of the T-shaped chord and they are each notched at their upper parts as at 7, see Fig. 4, to receive the web of the upper chord and are oppositely notched as at 8-8 to accommodate the bars 3-4 of the lower chord. It is apparent that the number of compression members 6 employed depends upon the length of the upper chord and that therefore the diagonally arranged tension members 9 may be increased or diminished in number accordingly. Where the tension members 9 lie beneath the lower ends of the compression members 6 they fit between the bars 3-4 the members 6 being notched as at 9^a to accommodate them, as clearly shown in Figs. 3 and 4. The struts 6 are welded to the upper and lower chords; the inclined ends of the lower chord are welded to the upper chord; the lower chord is welded to the compression members; and the tension members are welded to the upper chord and to the compression members, all at the time of manufacture at a central plant. To the bottom edge of the web of the upper chord is welded, at each end of said chord, a plate 10 adapted to rest upon girders as employed in floor and ceiling structures. Obviously, if the floor or ceiling is inclined these plates will vary in shape to take care of the pitch contemplated. At the time of manufacture

there is welded upon the flat top of the upper chord a plurality of vertical pins, pegs, or studs 11, disclosed and claimed in a co-pending application Serial No. 13,355 filed 5 March 5, 1925, which pins or the like are adapted to puncture metal lath, not shown, and sustain same in proper position upon the upper chord of my novel skeletonized joist. Obviously the number of pins employed depends upon the length of the skeletonized joist. By my above described joist I am enabled to manufacture at a central plant desired and scientifically calculated sizes and ship ready for erecting skeletonized 10 joist of greater strength and less weight than joist now employed and at the same time provide joist ready to accept and retain in secured position metal lath. Should it be necessary to leave an opening in the floor 15 for stairs, well, elevator, vent or the like the compression members 6 are apertured at 12 in the connection since supporting or other structural parts may be bolted thereto, the apertures 12 being used to accommodate the 20 bolts. This is a very important feature not previously used in connection with skeletonized joist, steel joist, or bar-joist.

It will now be apparent that I have devised a novel and useful construction which 25 embodies the features of advantage enumerated as desirable in the statement of the invention and the above description and while I have in the present instance shown and described the preferred embodiment 30 thereof which has been found in practice to give satisfactory and reliable results, it is to be understood that the same is susceptible 35 of modification in various particulars without departing from the spirit or scope of the invention or sacrificing any of its advantages.

Having thus described my invention, what I claim as new and desire to secure by Letters Patent, is:

45 1. A skeletonized joist comprising an upper chord of T-shaped cross section, a lower chord composed of a pair of spaced bars, a series of flat compression members between the chords, said members being notched at 50 the top to embrace the stem of the T-shaped chord and at each bottom corner to embrace said bars, and tension members between the chords the lower portions of which fit between said bars and extend under the compression members.

55 2. A skeletonized joist comprising an upper chord of T-shaped cross section, a lower chord composed of a pair of spaced bars, a series of flat compression members between 60 the chords, said members being notched at the top to embrace the stem of the T-shaped chord and at each bottom corner to embrace said bars, and tension members between the chords the lower portions of which fit between 65 said bars and extend under the com-

pression members, said compression members being notched at a point between the bar notches to embrace said tension members.

3. A skeletonized joist comprising a T-shaped top chord, a bottom chord composed 70 of a pair of bars bent upwardly at their ends to meet the top chord and spaced apart sufficiently to embrace the stem of the T, and a compression member between said chords slotted at the top to embrace the stem 75 of the T and secured at its lower corners to the bars of the bottom chord.

4. A skeletonized joist comprising a T-shaped top chord, a bottom chord composed 80 of a pair of bars bent upwardly at their ends to meet the top chord and spaced apart sufficiently to embrace the stem of the T, a compression member between said chords slotted at the top to embrace the stem of the 85 T and secured at its lower corners to the bars of the bottom chord, and a diagonal tension member between said chords secured above to the stem of the T and embraced below by the bars of the bottom chord at the base of said compression member. 90

5. A skeletonized joist comprising a T-shaped top chord, a bottom chord composed 95 of a pair of bars bent upwardly at their ends to meet the top chord and spaced apart sufficiently to embrace the stem of the T, and a compression member between said chords slotted at the top to embrace the stem of the T and notched at its lower corners to embrace 100 the bars of the bottom chord and hold them in proper spaced position.

6. A skeletonized joist comprising a T-shaped top chord, a bottom chord composed of a pair of bars bent upwardly at their ends to meet the top chord and spaced apart sufficiently to embrace the stem of the T, a 105 compression member between said chords slotted at the top to embrace the stem of the T and notched at its lower corners to embrace the bars of the bottom chord, and a diagonal tension member between said 110 chords secured above to the stem of the T and embraced below by the bars of the bottom chord at the base of said compression member.

7. A skeletonized joist comprising a T-shaped top chord, a bottom chord composed of a pair of bars bent upwardly at their ends to meet the top chord and spaced apart sufficiently to embrace the stem of the T, a compression member between said chords 115 slotted at the top to embrace the stem of the T and notched at its lower corners to embrace the bars of the bottom chord, and a diagonal tension member between said 120 chords bent upwardly at each side of its center to meet the stem of the T and having its lower central portion embraced by the bars of the bottom chord and lying beneath the end of said compression member. 125

8. A skeletonized joist comprising a T- 130

shaped top chord, a bottom chord composed of a pair of bars bent upwardly at their ends to meet the top chord and spaced apart sufficiently to embrace the stem of the T, a series of compression members between said chords slotted at the top to embrace the stem of the T and secured at their lower corners to the bars of the bottom chord, and diagonal tension members between said chords each of which is secured above to the stem of the T adjacent an end of a compression member and embraced below by the bars of the bottom chord at the base of an adjacent compression member.

In testimony whereof, I have hereunto signed my name.

GEO. F. PAWLING.
